CLAIMThe ornamental design for a surface for a bottle, as shown
and described.**DESCRIPTION**

FIG. 1 is a front view of the surface for a bottle;
FIG. 2 is a rear view of the bottle of FIG. 1; and,
FIG. 3 is a side view of the bottle of FIG. 1;
The structure shown in broken lines in FIGS. 1—3 is not part
of the design sought to be patented.
The characteristic feature of the claimed design resides in
the surface ornamentation shown in the claimed surface for
a bottle.
